UNITED STATES PATENT OFFICE.

JOHN W. SAMPLES, OF SUE, WEST VIRGINIA.

SHIPPING CRATE.

Application filed October 6, 1926. Serial No. 139,891.

This invention aims to provide a crate which may be folded up into small compass when not in use, novel means being provided for displaying addresses on the crate.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

- 20 Figure 1 is a top plan;
- Figure 2 is a side elevation;
- Figure 3 is an end elevation;
- Figure 4 is a cross section wherein the sides have been folded inwardly;
- 25 Figure 5 is a side elevation wherein the folding operation has been carried a step further than in Figure 4, parts appearing in section; and

Figure 6 is a plan view illustrating part 30 of the mechanism for displaying the address.

The device forming the subject matter of this application is a crate, it being understood that the term "crate" is to be construed as meaning any kind of a container which may be constructed in accordance with the claims of this invention. The foregoing definition being understood, it may be stated that the crate (which may be made of any desired material) includes a base 1 made up of corner posts 2, the corner posts being connected at the ends of the crate by sills 3 to which a bottom 4 is secured. Side walls 5 are provided, and are equipped at their ends and near to their lower edges with trunnions 6 that are journaled in the posts 2, the construction being such that the side walls 5 are hingedly mounted, for inwardly swinging movement as shown, for instance, in Figure 4. The side walls 5 are supplied at 40 their ends, and at their upper edges, with projections 7 adapted to be received in seats 8 that are formed in end walls 9, the posts 10 of the end walls being united by tongue and groove hinges 11 with the upper ends of the posts 2 of the base 1. In the lower portions of the end walls 9, extensions 12 are

slidably mounted. The crate includes a top 14 having a lid 15 which is hingedly mounted as at 16. There are projections 17 on the corners of the top 14, and these projections are adapted to be received in seats 18 formed in the upper parts of the end walls 9. Latch hooks 19 are pivoted to the posts 10 of the end walls 9. There are keepers 20 which project horizontally from the upper rails of the side walls 5, and the lower rails of the side walls are supplied with depending keepers 21.

When the crate is set up for use, the end walls 9 stand vertically, the projections 7 on the side walls 5 are received in seats 8 of the end walls 9, the latch hooks 19 are engaged with keepers 20, the top 14 is disposed above the side walls 5, and the projections 17 on the top 14 are received in the seats 18 that are formed in the upper portions of the end walls 9, as shown in Figure 4.

In order to collapse the crate, the latch hooks 19 are disengaged from the keepers 20, the end walls 9 first are swung outwardly 80 a little, on the hinges 11, to disengage the projections 17 of the lid 14 from the seats 18 in the end walls 9, and to disengage the projections 7 of the side walls 5 and the seats 8 in the posts 10 of the end walls 9. The top 14 then is lifted off and the extensions 12 are slid upwardly in the end walls 9 until the bottom rails of the extensions 12 abut against the bottom rails of the end walls 9. The side walls 5 are folded inwardly until 90 they overlap the bottom 4, as shown in Figure 4. The top 14 is placed on the end walls 5 after they have been folded inwardly as in Figure 4. The end walls 9 are folded over on top of the part 14, as shown in Figure 5, and the hook latches 19 are engaged with the keepers 21 to hold the crate in collapsed condition.

The foregoing description relates peculiarly to those characteristics of the crate 100 which enable it to be folded up into small compass for return shipment.

Passing now to features which relate to the displaying of the address, it will be observed that there is a card holder 22 on the top 14, the holder 22 being of any desired construction, and being adapted to receive a card 23 which displays, as shown at 105 24, the address of the person to whom the crate is to be sent. During the shipment 110 of the merchandise, the lid 15 is so mounted that the card 23 is uppermost and the ad-

dress 24, therefore, can be read without difficulty. When, however, the crate, in collapsed form, is being returned to the original shipper, then the top 14 is turned upside-down, so that the card holder 22 and the card 23 are underneath, the address of the person to whom the merchandise was shipped in the crate, being then concealed. On the outer surface of one of the end walls 9, there is a holder 25 adapted to retain a card 26 on which the return address is inscribed as shown at 27. The card holder 25 is practically covered by a plate-like guard 28 having fingers 29 extending around the card holder 25 transversely and forming a means whereby the guard is slidably mounted on the card holder 22. The fingers 29 are connected at their inner ends, as shown at 30, to one of the spindles 31 that form part of the extension 12 of the end walls 9, the spindles of the extension being slidable in the lower rail of the end wall 9. When the crate is set up as shown in Figures 1 and 3, the extensions 12 are slid downwardly along the bottom 3, to close the ends of the crate, and, then, the guard 28 is carried downwardly so that it covers the card 26 in the holder 25. The return address thus is covered, as shown in Figure 3, and the shipping address is exposed, as shown at 24 in Figure 1. When the crate is collapsed and when the top 14 has been turned up-side-down, as hereinbefore explained, the address at 24 cannot be seen, but if the extensions 12 are shoved inwardly on the end walls 9, the guard 28 is carried into such a position that the card 26 and the address 27 are disclosed, as depicted in Figure 6. It is necessary to slide the extensions 12 inwardly, when the crate is collapsed, so that the extensions 12 will not project out from the ends of the

collapsed crate—an observation which will be understood readily when Figure 5, and particularly the left hand end of Figure 5, is noted.

45

What is claimed is:

1. In a device of the class described, a base including corner posts and a bottom supported thereby, side-walls, means for mounting the side walls hingedly, end walls hinged to the posts and spaced from the bottom, extensions slidable on the end walls and bridging the space between the end walls and the bottom, a top, means for supporting the top removably in spaced relation to the bottom, and cooperating members including an address carrier and a guard therefor, one of said cooperating members being secured to one of the side walls, and means for connecting the other of said cooperating members to the extension of said side wall for movement with said extension, whereby the guard, in a predetermined position, will reveal the address carrier.

55

2. A device of the class described, comprising a bottom and a wall mounted for swinging movement, an extension slidable on the wall, toward and away from the bottom, cooperating members including an address carrier and a guard therefor, one of said cooperating members being secured to the side wall, and means for connecting the other of said cooperating members to the extension for movement with the extension, whereby, when relative movement between 70 said cooperating members takes place, the guard, in a predetermined position, will reveal the address carrier.

75

In testimony that I claim the foregoing as my own, I have hereto affixed my signature.
